UNITED STATES PATENT OFFICE.

SAMUEL WINSOR, WILLIAM G. HOLT, AND PALMER B. GILBERT, OF CASSVILLE, WISCONSIN.

NUT-LOCK.

SPECIFICATION forming part of Letters Patent No. 406,074, dated July 2, 1889.

Application filed September 5, 1888. Serial No. 284,677. (No model.)

To all whom it may concern:

Be it known that we, SAMUEL WINSOR, WILLIAM G. HOLT, and PALMER B. GILBERT, of Cassville, Grant county, Wisconsin, have 5 invented certain new and useful Improvements in Nut-Locks; and we do hereby declare the following to be a full, clear, and exact description of the invention, such as will enable others skilled in the art to which it appertains 10 to make and use the same.

Our invention relates to an improvement in nut-locks, the object of the same being to provide a simple and inexpensive device for locking nuts to bolts that will present a neat 15 appearance and one that can be applied in an instant without the employment of specially designed tools or skilled labor.

With these ends in view our invention consists in the parts and combinations of parts, 20 as will be more fully described, and pointed out in the claim.

In the accompanying drawings, Figure 1 is a view in perspective, showing the bolt, nut, and lock detached. Fig. 2 is a view in elevation, showing the screw-threaded end of the 25 bolt, the nut, and lock in section; and Fig. 3 is a transverse sectional view on the line $x-x$ of Fig. 2.

A represents a bolt of any size and shape, 30 the screw-threaded end of which is provided with a groove a' , starting from the end of the bolt and running wholly or partly throughout the screw-threaded portion thereof. This groove can be any shape and size, 35 and is adapted to receive the tongue c' of the cap C. This cap C is simply a hollow box having an open face and four sides, the closed face having a central perforation c for the passage of the screw-threaded end of the bolt.

40 The tongue c' projects into this perforation, and hence it will be seen that when the cap C is placed on the screw-threaded end of the bolt, with the tongue c' resting in the groove, the cap is held against rotary movement on 45 the bolt and the latter held against rotary movement on the cap.

The nut B can be of any shape or size, and

the cavity in cap C is shaped to snugly receive the nut and rest with the free edges of its walls c^2 flush with the rear face of the 50 nut. The nut can be of any of the shapes commonly employed, and is provided on its edges with grooves b , which, in the present instance, are continuous and form a channel around the perimeter of the nut. Two walls 55 c^2 of the cap C are provided with perforations c^3 , located opposite each other and adapted to register with the groove b in the nut B when the parts are assembled for the passage of a pin, wedge, or spring-key D, which latter is 60 adapted to prevent the cap from moving off the nut.

To assemble the parts, the nut is first secured home and the cap passed onto the end of the bolt, with its tongue in the groove of the 65 bolt. If the angles of the cavity or recess in the cap should not register with the angles or corners of the nut, the latter can be turned forward or backward slightly, as the case may be, until the cap can be passed onto the nut. 70 The cap prevents the slightest independent rotary movement of the nut and bolt, while the pin, wedge, or key D prevents an accidental displacement of the cap, and when the parts are once assembled the jarring or tremulous motion of the machinery or structure to which the lock is applied cannot possibly 75 displace or loosen the nut. To remove the nut, it is simply necessary to withdraw the pin, wedge, or key and remove the cap. This leaves 80 the nut free to be removed by a wrench in the ordinary manner.

We are aware of United States Patents Nos. 347,764, 91,188, and 140,119, and we do not desire to claim herein the construction shown 85 in said patents; but

What we do claim, and desire to secure by Letters Patent, is—

In a nut-lock, the combination, with the threaded bolt A, provided with a longitudinal groove a' , of the nut B, provided upon each of its sides with a groove b , the cap C, recessed to adapt the same to fit over the nut, 90 said cap being provided with a central per-

foration for the passage of the bolt, a tongue or tenon c' , adapted to fit within the groove a' of the bolt, and two apertures c^3 , which, when said cap is placed over the nut, align 5 with one of the grooves b , and the locking pin or key D , adapted to pass through the aligned groove and openings, for the purpose specified.

In testimony whereof we have signed this

specification in the presence of the two sub- 10
scribing witnesses.

SAMUEL WINSOR.
WILLIAM G. HOLT.
PALMER B. GILBERT.
